REVOLVING BASE FOR POOL TABLE
Fred E. Knoedler, *%* Knoedler Manufacturers Inc.,
P.O. Box 397, Streator, Ill. 61364
Filed Oct. 23, 1965, Ser. No. 503,275
4 Claims. (Cl. 248—188.2)

ABSTRACT OF THE DISCLOSURE

Revolving base for pool table having a rectangular frame for the pool table, said frame being supported from a hollow metal drum, a plurality of ball bearing mounted rollers disposed along the lower edge of said drum, a base drum for supporting the said drum, a plurality of rollers disposed about the open end of said drum for engaging the lip of the base drum, the rollers having a flange on each side of the roller that extends adjacent the lip of the base drum for stabilizing the arrangement, and adjusting leveling screws for assisting the leveling of the table for use during the time the table is used.

Specification

The present invention relates to a revolvable base for a pool table, and more particularly relates to revolvable mechanisms incident to supporting a revolvable pool table mounted on such base.

While the concept of a revolvable table, chair or other pedestal is well known, they are found to be unstable for use with a pool table or billiard table, since they are found to slightly rock just enough for unwanted displacement of the balls. By providing a substantially large diameter for such a revolvable base, the table is substantially level at all times, so that the table and assembly can be moved without unwanted rolling of the balls. Of course the table top is not revolved until the balls have stopped rolling after play. In an important embodiment of the present invention, the revolvable base for pool and billiard tables are made for home use in recreation rooms which are not generally sufficiently large enough for a pool table without using a short cue stick at least part of the time and this has been found to distract or ruin the skill of the game. By selecting the position of the revolvable table top base combination of the present invention, the table may be set close to one corner so that the table just clears two walls when turned, and the player is provided with ample room from either of the other two directions.

Another feature of the invention is that leveling feet or mechanisms may be provided at the base or bottom of the stationary drum or base of the arrangement for adjusting uniformly the table top.

The present invention contemplates providing a turntable in which a roller is attached to engage an upper lip of a base drum, and for mounting a pool table supporting drum from the rollers to achieve the objects and advantages of the present invention.

An object of the invention therefore is to provide a revolvable pool table top that is adapted to be used in confined spaces such as basements, recreation rooms and alike, and yet able to maintain the necessary skill in practice of the game.

The above and other objects and advantages of the invention will become apparent upon full consideration of

2

the following detailed description and accompanying drawings in which:

FIGURE 1 shows a generally perspective view of a revolvable base for a pool or billiard table in accordance with the present invention.

FIGURE 2 shows a plan view of the revolvable supporting or mounting drum and frame, and in which the billiard or pool table has been removed for purposes of illustrating the component structural features of the invention.

FIGURE 3 shows a front or side elevation view of FIGURE 2 in which the billiard or pool table is shown partially broken away; and

FIGURE 4 shows an enlarged cross-sectional broken view showing the features of the present invention.

Referring now to the drawings there is shown a pool or billiard table top 10 having the conventional pockets and corners, and in which there is an angle iron frame 12 of a nature for supporting the table 10 by means of screws or bolts that are applied to extend through holes 14, 14, the bolts 16 being illustrated in FIGURE 3. The table is of conventional construction having a slate plate or top 20 over which is provided a felt surface 22 in the well known manner. The frame 12 is secured by bolts or a weld-joint 24 to a rotatable drum 28 for providing a mounting relation for the table top 10 with respect to a base drum 30.

The base drum 30 is mounted from the ground surface 32 and the level of the table may be adjusted by means of the leveling bolts 34, 34. Intermediate the rotatable drum 28 and the base drum 30 there are provided a series of rollers 36, 36, so that the roller 36 is mounted from the drum 28 and in which the rolling surface of the roller 36 engages the upper lip 40 of the base drum 30. The rollers 36 are mounted from bolts 42 which extend from the lower edge of the rotatable drum 28.

Supporting structural bars 46, 46 may be criss-crossed throughout the open mount of each of the drums 28, 30 for adding rigidity and support to the drums.

The rollers 36 may be mounted by a ball bearing assembly so that the roller is turned with the least amount of applied force to overcome static friction. Although not shown, the structural bars 46, 46 may be replaced by a steel disc which is welded into the drum just above the ball bearing assembly of the upper drum and also within the lower drum, immediately below the lip 40, so that the rigidity of the construction is obtained.

The lower drum 30 is of a slighter diameter than the large drum 28 as illustrated in the drawings.

By means of this construction, the level characteristic of the pool or billiard table is maintained effective at all times for all positions of rotation.

Additional embodiments of the invention in this specification will occur to others and therefore it is intended that the scope of the invention be limited only by the appended claims and not by the embodiment described hereinabove. Accordingly, reference should be made to the following claims in determining the full scope of the invention.

What is claimed is:

1. A revolvable base for a pool table comprising a generally rectangular frame for mounting said table, a revolvable upper drum comprising an upright cylinder with open ends, said frame being mounted on the upper end of the cylinder, a plurality of ball-bearing mounted rollers

disposed along the lower edge of the cylinder, and a base drum supporting the upper drum, said base drum comprising a cylinder with an open upper end, said rollers engaging and riding upon the upper end edge of said base drum.

2. The invention according to claim 1 wherein leveling screws are disposed on the base drum mounted depending from the bottom portion thereof.

3. The invention according to claim 2 wherein each drum is provided with reinforcing members disposed therewithin respectively proximate to the lower edge of the upper drum and to the upper edge of the lower drum.

4. A rotatable base for a billiard table comprising a hollow metal base drum defined by a cylinder having an upper lip substantially in a plane at right angles to the axis of said drum, a revolvable drum of slightly different

10 diameter mounted on the base drum, said revolvable drum having open ends with a plurality of rollers disposed about the lower end thereof for engaging the lip of the base drum, and a mounting frame disposed at the upper end of

15 said revolvable drum for mounting a playing table thereon.
